UNITED STATES PATENT OFFICE.

WILLIAM BORCHERT, OF ROCKFORD, ILLINOIS, ASSIGNOR OF ONE-HALF TO WILLIAM A. MCPHERSON, OF ROCKFORD, ILLINOIS.

DEVICE FOR SEALING WRAPPED PACKAGES.

1,061,039.

Specification of Letters Patent.

Patented May 6, 1913.

Application filed December 26, 1912. Serial No. 738,625.

To all whom it may concern:

Be it known that I, WILLIAM BORCHERT, a citizen of the United States, residing at Rockford, in the county of Winnebago and 5 the State of Illinois, have invented certain new and useful Improvements in Devices for Sealing Wrapped Packages, of which the following is a specification.

This invention relates to devices for sealing wrapped packages and more particularly to the sealing of loaves of bread which have been wrapped in paraffin paper or paper with a like or similar coating applied to the portion of the wrapper which is to be 15 sealed.

The object of this invention is to construct a sealing device for this purpose which shall be simple in its construction and inexpensive to manufacture and which shall 20 perform its functions automatically when wrapped packages have been passed through the device.

The further object is to provide a novel construction in which the sealing of the 25 packages shall be performed by a heating element and the sealed portion be held in a set position by a cooling member until the seal has become fixed.

In the accompanying drawings: Figure 30 1 is a plan view of the device, a portion of one of the runner plates being broken away. Fig. 2 is a side elevation of the sealing device with a portion of the heating guard plate broken away. Fig. 3 is a vertical section on the line 3—3 of Fig. 2. Fig. 4 is 35 a plan section on the line 4—4 of Fig. 2.

The sealing device may be suitably supported in a machine for automatically and mechanically wrapping loaves of bread or 40 on a convenient stand or rest where bread wrapped by hand may be quickly and conveniently passed through the sealer.

The longitudinal runner plates 1 consist of an upper and lower member spaced apart, 45 and the supporting brackets therefor are secured between said plates.

The heating elements 5 may be of a suitable construction, having here shown a common type of electric resistance heater in 50 which the current is supplied through the wires 6 to each of the two elements. The

heating elements 5 as shown are square and have an extended vertical flange 7 to each end thereof. To the flanges toward the forward end of the sealer is attached by the 55 bolts 8, a curved mouthpiece or entering guide-plate 9, there being a strip 10 of suitable non-heat conductive material placed between the plate 9 and the flange. The rear flanges of elements 5 are connected to 60 the side guide-plates 11 in a similar manner, the non-conductive material serving to stop the passage of heat from the elements 5 to the side plates 11 which plates act as cooling elements. The guard plates 12 are 65 secured to the plates 9 and 11 and serve to protect the operator from being burned and the heating elements from being damaged. Thus a heating element and a cooling element form an independent member and the 70 two such members are held yieldingly in position by the slidable plates 13 held between the upper and lower members of the runners 9. Two adjacent plates 13 are fastened at opposite ends to the side plates 75 which are held yieldingly in position by the coiled springs 14 having one end attached to each of two adjacent plates 13 and to the ends thereof that are secured to the side plates. The pins 15 by which the springs 80 are connected to the plates, contact the runners and thereby limit the inward movement of the side members, said pins being adjustable in the holes 16 so as to vary the width of opening between the side members 85 to suit the size of the packages being wrapped.

The operation of the sealing device is as follows: The heating elements are maintained heated to a sufficient degree and 90 loaves of bread or any other article wrapped in paraffin paper or paper to which has been applied a similar coating at the sealing portions, are placed upon the runners in front of the mouth pieces 9, passed along 95 the runners coming in contact first with the heating elements and then with the cool side members. The side members are to be adjusted to suit the width of the package being wrapped, and when a package is 100 passed between the side members it will be compressed to a slight degree therebe-

tween because of the tensional support of said side members. As the ends of the package that are to be sealed contact the heated elements the paraffin or like substance which the paper contains, becomes diffused, and passing to the cool sides of the device are cooled, thus setting the diffused substance and sealing the package. The packages may be entered one after another, each succeeding package moving the preceding package along. The time required for diffusing the substance is but momentary but of course varying with the degree of temperature to which the heating elements are maintained, so that packages may be passed through the device as quickly as they can be wrapped.

It will be seen that the operation of the sealing device is exceedingly simple and enables packages to be sealed very economically and quickly, thus making it a great labor saving device that maintains a high efficiency.

I claim as my invention:

1. A device for sealing wrapped packages comprising supports carrying two oppositely positioned side walls having longitudinal continuous faces forming a passage having an entrance and discharge end, and a heating member carried by each of the side walls, oppositely positioned, and at a point intermediate the entrance and discharge ends of the walls, the heating face of each member being substantially in the plane of said side wall faces, and the outer edges of the heating members adjacent the side walls being heat insulated from said side walls.

2. A device for sealing wrapped packages comprising supports carrying two oppositely positioned side walls, each comprising a spaced entrance and body end lying substantially in the same plane, a heating member interposed between each of said entrance and body portions and connected thereto, the face of the heating member forming with the faces of its adjacent side walls, a continuous wall, and means connecting the opposite side walls and the base for holding said walls yieldingly in position.

3. A device for sealing wrapped packages comprising supports, two oppositely positioned side walls having longitudinal continuous faces forming a passage, the entrance end of the walls having diverging wing sections, an opening in each wall, the openings oppositely positioned and at a point intermediate said entrance end and the opposite end of the walls, a heating member positioned in each of said openings having its heating face substantially in the same plane as that of its side wall and forming with its side wall a continuous face, and means connecting the two opposite walls

and the supports and adapted to hold the walls yieldingly in position.

4. A device for sealing wrapped packages, comprising supports, two oppositely positioned side walls having longitudinal continuous faces forming a passage, the entrance end of the walls having diverging wing sections, an opening in each wall, the openings oppositely positioned and at a point intermediate said entrance end and the opposite end of the walls, a heating member positioned in each of said openings having its heating face substantially in the same plane as that of its side wall and forming with its side wall a continuous face, the heating members being secured to the side walls by heat insulating connections, and means connecting the two opposite walls and the supports and adapted to hold the walls yieldingly in position.

5. A device for sealing wrapped packages comprising a support, two oppositely positioned side walls having longitudinal continuous faces forming a passage having an entrance and discharge end, an opening in each side wall, oppositely positioned and at a point intermediate the entrance and discharge ends thereof, a heating member positioned in each opening having its heating face in a plane substantially with that of its side wall, a transversely disposed carrying member attached to each side wall adjacent each end thereof and being slidably held by said support, and means connecting the adjacent carrying member for holding the side walls yieldingly in position.

6. A device for sealing wrapped packages comprising a support, two oppositely positioned side walls having longitudinal continuous faces forming a passage having an entrance and discharge end, an opening in each side wall, oppositely positioned and at a point intermediate the entrance and discharge ends thereof, a heating member positioned in each opening having its heating face in a plane substantially with that of its side wall, each side wall carrying fixedly a supporting member adjacent its two ends, said supporting members being carried by said support and movable thereon transversely to said passage to move the side walls bodily, and means for holding the side walls yieldingly together.

7. A device for sealing wrapped packages comprising two parallel disposed runners having an upper and lower member, a support for the runners, and a side wall positioned to the outer side of each runner, parallel therewith and having an opening in its face at a point intermediate the ends thereof, the openings being oppositely positioned, a heating member positioned in each opening having its heating face in a plane substantially with that of its side wall, transversely disposed supports fixedly secured to

said side walls and being held slidale between said upper and lower members of the runners, and means for holding the two side walls yieldable bodily against outward pressure, such movement being accomplished through said supports slidale in the runners.

In testimony whereof I have hereunto set my hand in presence of two subscribing witnesses.

WILLIAM BORCHERT.
